(57) **CLAIM**

The ornamental design for a shoe, as shown and described.

DESCRIPTION

FIG. 1 is a bottom perspective view of a shoe showing the claimed design, the front and top views thereof form no part of the claimed design;

FIG. 2 is a rear view thereof;

FIG. 3 is a left side view thereof;

FIG. 4 is a right side view thereof; and,

FIG. 5 is a bottom view thereof.

The dashed broken lines in the figures show portions of the shoe that form no part of the claimed design.

The dot-dash broken lines in the figures show boundaries that form no part of the claimed design.
